UNITED STATES PATENT OFFICE.

JOSEPH GARGAN, OF PEABODY, MASSACHUSETTS.

BOOT AND SHOE CONSTRUCTION.

Application filed April 15, 1924. Serial No. 706,763.

To all whom it may concern:

Be it known that I, JOSEPH GARGAN, a citizen of the United States of America, residing at Peabody, in the county of Essex and State of Massachusetts, have invented new and useful Improvements in Boot and Shoe Constructions, of which the following is a specification.

This invention relates to improvements in 10 the construction of boots and shoes, and more particularly to the uppers thereof.

A preferred object of the invention is the provision of a support to the shoe upper by forming the same of a plurality of pieces of 15 material of substantially the same width.

Another object of the invention is to provide a construction of back-stay which will prevent what is known as "heel cord chafing," which is produced by the forming of 20 wrinkles in the shoe-upper directly over the cords in the heel causing the stitches in the back-stay to break and rendering the shoe weak and unsightly.

Still another object of the invention is the 25 forming of the shoe-upper from scrap stock or material which would otherwise be wasted, due to the making of the same from a plurality of pieces instead of the customary one or two, as at present, which results in much more economical shoe production 30 than is possible at present.

A still further object of the invention is the joining of the upright seams of the sections of the shoe-upper at points removed 35 from the central back portion thereof.

These and other objects and advantages of the invention will be apparent from a reading of the specification, the following being a detailed description of the present 40 preferred embodiment which is illustrated in the accompanying drawing, wherein:

Figure 1 is a view in perspective, in side elevation, showing the position of attachment of the back-stay to one of the side portions of the upper; and

Figure 2 is another view in perspective, the same showing the back of the shoe and the manner of attaching the back-stay to the side portions of the upper.

50 Referring to the drawings, the numeral 1

designates the vamp of a shoe and the numeral 2 the sole thereof, these portions being preferably made of rubber and substantially integral, though it is to be understood that the same may be made of leather or 55 any other suitable material.

In the present case, the top or so-called upper of the shoe is preferably made of leather and formed in three separate sections, the numerals 3 and 4 designating the 60 side portions thereof and 5 the back-stay, which sections are secured together in any suitable way, in the present instance, by stitches 6. The side sections 3 and 4 and back-stay 5 are suitably bound at their upper portion by the edging 7, and secured at their bottom portion to the vamp 1 by means of stitches 8 or the like.

As best shown in Fig. 2, the back-stay 5 is formed of a wide strip of leather or other 70 material and joined to the side-portions 3 and 4 at a point removed from the central back portion of the upper. The joining of the three sections of the upper in this manner avoids the necessity of lapping the 75 edges at the back of the shoe, thus precluding the formation of wrinkles at that portion which results in injury to the feet of the wearer and weakening that part of the shoe due to the breaking of the stitches by the constant wrinkling. Also, by providing only a single thickness at the back of the shoe, instead of the lapped edges now employed, the shoe structure is strengthened and the sections of the upper do not separate due to breaking of the stitches resulting from such wrinkling.

Various changes and modifications may be made in the details of construction and design of my shoe without departing from 80 the spirit of the invention; but it is to be understood that such changes and modifications are within the scope of my inventive concept, except as the same may be limited in the following claims:

Having thus described my invention, what I claim as new is:

1. A shoe structure comprising a vamp, and an upper formed of a plurality of sections, each of substantially equal width, said 100

2 sections being permanently secured to each other at points removed from the central back portion of the upper.

2. A shoe structure comprising a vamp made of rubber material, an upper made of nonrubber material and formed of two side portions and a back-stay, said back-stay

being joined to the side portions at points all substantially removed from the central back portion of the upper, and a binding ¹⁰ strip at the top of the upper.

In testimony whereof I affix my signature.

JOSEPH GARGAN.
